UNITED STATES PATENT OFFICE.

GEORGE W. WALTENBAUGH, OF SAN FRANCISCO, CALIFORNIA.

GAS-ENGINE IGNITING APPARATUS.

SPECIFICATION forming part of Letters Patent No. 543,116, dated July 23, 1895.

Application filed December 17, 1894. Serial No. 532,090. (No model.)

To all whom it may concern:

Be it known that I, GEORGE W. WALTENBAUGH, a citizen of the United States, residing in the city and county of San Francisco, State of California, have invented certain new and useful Improvements in Gas-Engine Igniting Apparatus; and I hereby declare the following specification and drawings therewith to be a complete description of my invention, with the manner of constructing and applying the same.

My improvements relate to what is called "electrical igniting apparatus for gas-engines," wherein the charge of gas and air is ignited by a spark caused by the disengagement of electrodes placed in the engine-cylinder or the combustion-chamber thereof.

My invention consists in pivoting the stationary electrode on an adjustable stem passing out through the walls of the cylinder and insulated therefrom, the normal or non-active position of the electrode being maintained by a spring or springs placed beyond the zone of injurious heat, and so the springs and their connected mechanism cannot be affected thereby.

My invention further includes mechanism to accomplish this object, as shown in the drawings herewith, in which—

30 Figure 1 is a partial view of a gas-engine cylinder provided with my improved igniting apparatus. Fig. 2 is a longitudinal section through the devices for operating the stationary electrode in the electric circuit, with a movable one for igniting the charge. Fig. 3 is a cross-section on the line $x-x$ of Fig. 2. Fig. 4 is a diagram in the opposite plane, showing the action of the two electrodes in the combustion-chamber of the engine.

40 Similar letters of reference are employed to designate like parts in the different figures of the drawings.

The main cylinder A is made with double walls and an annular cooling water-space B in the usual manner. A separate chamber C is attached to the main cylinder A on the line D, containing an induction-valve E for gas and air and an exhaust-valve F for the discharge of burned or spent gases. These 50 valves E and F are opened by cams G' G" on the shaft H and are closed by the coil-springs

I' I". The shaft H is driven by the bevel-wheels J, having a proportion as two to one of the main crank-shaft, to which the vertical shaft K is geared, thus opening the valves 55 E and F at alternate revolutions of the engine-shaft and at alternate strokes of the piston L in the usual manner of operating gas-engines.

Between the valves E and F, preferably in 60 the axis of the cylinder A and combustion-chamber C, I place a shaft or spindle M, driven by the miter-wheels N. On the bottom or inner end of this spindle M, I provide at right angles thereto an extension O, which forms 65 the negative electrode.

The positive or stationary electrode P is mounted on a cylindrical stem Q, pivoted on a cross-pin R, as seen in Figs. 2 and 4. This electrode P is flat at its rear end, as seen in 70 Fig. 4, and is pressed against by a sliding rod S, extending back into a rear chamber T, where a coil-spring U presses continually against the head V on the rod S, thrusting it forward, pressing the cross-head W at the other 75 end against the rear end of the electrode P, as shown by dotted lines in Fig. 4. This tends to hold the electrode P elastically in alignment with the rod S and hollow stem Q, so that when engaged by the rotating electrode 80 O and pressed to one side, as shown in Fig. 4, it instantly regains its normal position by resilient action of the spring U and longitudinal movement of the rod S, causing also instant release between the electrodes O and 85 P, and a resulting spark that ignites the contained charge in the engine-cylinder A.

The electrode P is connected by a wire X to the positive pole of an electric battery, and the other electrode O by a wire Y to the other 90 pole of the battery, the current passing through the connected part of the engine in the one case and through rod S, stem Q, and surrounding metallic parts insulated from the cylinder A, as seen at d in Fig. 2, in the 95 other case.

In mounting the stationary or positive electrode P, I first insert a screw-threaded shell c through the side of the cylinder A. Inside this shell c I place a tapered sleeve or second 100 shell m, around which is the insulating material d. On the outer end of this shell m is a

nut *n* and a washer *o*, by which the shell is drawn outward, clamping and securing the insulating material *d* around the shell *m*, also against the end of the outer screw-shell *c*, by means of a washer *o*. The inner shell *m* extends through the nut *n* to receive the cylindrical extension *f*, which is screw-threaded on its interior and receives at its outer end the hollow plug or spring-chamber *T*, as seen in Fig. 2. The stem *S* is moved at the same time with the part *T* by means of a pin *l*, fitting into an annular groove *p*. This adjusts the electrode *P* outward or inward and determines the length of the arc of contact, as indicated by dotted lines *q* in Fig. 4. A jam-nut *g* is provided to prevent false movement of the plug *T*, stem *S*, and the electrode *P*. The central stem *S* is prevented from turning by means of the rectangular head *W*, fitting in the slotted end of the hollow stem or sleeve *Q*. This latter fits loosely in the insulated shell *m*, also in the hollow plug or chamber *T*, and is prevented from turning by a pin *h* fitting loosely in a groove *i*, as seen in Figs. 2 and 3.

The shell or extension *f* is made of sufficient length to remove the spring *U* and its connected parts from the intense heat of the cylinder, and thus secure endurance and reliable action of the electrodes.

The spring *U* may be a deflecting one, or in any of the well-known forms that will maintain an elastic pressure on the stem *S* and the electrode *P*. It will be seen that when thus constructed no deflecting part of the apparatus is exposed to high temperature, and the electrode *P*, being inflexible, can be made stiff and in durable form, also be readily adjusted from the outside, and removed or replaced in a moment's time, independent of the shells *c* and *m* and the insulation *d*. It will also be understood that the movable electrode *O* can have a rotary, oscillating, or vibratory movement, the action being the same in respect to the stationary electrode *P* when the latter is arranged according to my invention.

Having thus described the nature and ob-

jects of my invention, what I claim as new, and desire to secure by Letters Patent, is—

1. In a gas engine igniting apparatus, a pivoted electrode, inflexible or rigid in section, mounted on an adjustable hollow stem passing out through the walls of the cylinder, or the combustion chamber thereof; a movable rod passing through the supporting stem, provided with a flat face on its inner end bearing on a similar face on the electrode, so the latter will be elastically held in alignment with the stem, substantially as described.

2. In a gas engine igniting apparatus, a pivoted electrode of inflexible section, pivoted on a stem passing out through the side of the engine cylinder, or the combustion chamber thereof; a central rod therein, bearing on an electrode in the cylinder, and a spring at the outer end of the rod, the latter placed in a closed shell and removed from the engine cylinder, so as to not be affected by heat of the burning gases, in the manner substantially as described.

3. In gas engine igniting apparatus, a pivoted electrode within the cylinder, supported by a sliding stem, the latter supported and guided by a tapering insulated shell, and a nut to draw the shell outward in its conical seat, and thus clamp and confine insulating material at the sides and outer end of the conical shell, in the manner substantially as herein specified.

4. In gas engine igniting apparatus, a pivoted electrode; a supporting hollow stem moving in an insulated shell at one end, and in a hollow chamber or plug at the other end, the latter adjustable with the hollow stem, and containing a spring connecting to and operating or adjusting an electrode in the engine cylinder, in the manner substantially as described.

In testimony whereof I have hereunto affixed my signature in the presence of two witnesses.

GEO. W. WALTENBAUGH.
